UNITED STATES PATENT OFFICE.

ANTHONY PALUCH, OF DETROIT, MICHIGAN.

DESIGN FOR A CUFF-BUTTON.

46,181.

Specification for Design.

Patented July 28, 1914.

Application filed June 1, 1914. Serial No. 842,322. Term of patent 3½ years.

To all whom it may concern:

Be it known that I, ANTHONY PALUCH, a subject of the Czar of Russia, residing at Detroit, in the county of Wayne and State of Michigan, have invented a new, original, and ornamental Design for Cuff-Buttons, of which the following is a specification, reference being had therein to the accompanying drawing, forming part thereof.

Figure 1 is a side elevation of a cuff button, showing my new design; Fig. 2 is a rear elevation of the same, and Fig. 3 is a front elevation of the same.

I claim:

The ornamental design for a cuff button, as shown.

ANTHONY PALUCH.
